S. HOLMGREN.

SKEE ATTACHMENT.

APPLICATION FILED FEB. 7, 1920.

Patented Feb. 1, 1921.

INVENTOR:
Swan Holmgren,
BY his ATTORNEY:
A. M. Carlsen.

UNITED STATES PATENT OFFICE.

SWAN HOLMGREN, OF MILLTOWN, WISCONSIN.

SKEE ATTACHMENT.

1,367,185.

Specification of Letters Patent.

Patented Feb. 1, 1921.

Application filed February 7, 1920. Serial No. 357,101.

To all whom it may concern:

Be it known that I, SWAN HOLMGREN, a citizen of the United States, residing at Milltown, in the county of Polk and State 5 of Wisconsin, have invented a new and useful Skee Attachment, of which the following is a specification.

My invention relates to attachments for skees, and the object is to provide a pair 10 of skees with a seat connecting them and means for propelling and for steering the coasting device thus formed.

In the accompanying drawing:—

Figure 1 is a plan view of my invention. 15 Fig. 2 is a side elevation of Fig. 1. Fig. 3 is a section on the line 3—3 in Fig. 2. Fig. 4 is a detail top view of certain parts of the device. Fig. 5 is a side view of the staff by which the device is pushed forward.

20 Referring to the drawing by reference numerals, 6 designates a pair of skees with their usual toe straps removed and my new attachment secured upon them. Said device comprises two metal plates 7, secured 25 one upon the middle of each skee by screws 8. Each of said plates is provided with a bracket 9 and an upstanding arm 10.

Pivoted at 10^x to the brackets 9 are the legs 11 of a horizontal bridge bar 12, which 30 thus connect the skees together as a pair of runners. Pivoted at 13 upon the middle of the bridge 12 is a cleat 14, upon which a seat 15 is secured.

The cleat is provided with two bolts 16 35 having elongated eyes 17, in which engage elongated eyes 17^x of two light metal rods, 18, whose front ends are provided with eyes 19, retained upon the front tips 20 of the skees by pins 21 or other suitable means.

40 22 are foot rests which may be secured on the arms 10 or other suitable part of the frame work. The upper ends of the rocker arms 10 are pivoted at 23 to the ends of a front cross bar 24, which bar is provided 45 with two forwardly directed pegs 25.

In Fig. 5 the staff 26 is provided in its lower end with a prong 27, and some distance therefrom with a cone-shaped collar 28, having a sharp edge 29 by which to engage in 50 the snow.

In the operation the occupant of the seat 55 takes hold of the staff 26 and, leaning forward some, he reciprocates with one or both hands the staff 26 in about the position shown in Fig. 2, so that either the prong 27

or the cone engages the icy or snowy ground and after each rearward push is pulled forward again. During such operation the feet of the rider may rest upon the arms 22, or if he is a large person he may 60 let the feet rest upon the skees near in front of the plates 7.

If during the propelling forward on about level ground, or in coasting down a hill side, it be desired to steer to either right or left, 65 the operator, having one of his lower limbs engaged between the pegs 25, presses to the desired side and thereby causes the arms 10 to tilt both skees laterally at the joints 10^x, whereby the curves 6^x of the skees steer the 70 skees to the desired side. During such tilting of the skees the elongated eyes 17, 17^x permit the rods 18 to adjust their lengths automatically as may be required for tilting. In general the rods 18 serve as braces to 75 aid in preventing undue spreading of the front ends of the skees.

The device as a whole is especially adapted for riding on ordinary snow-covered roads in the tracks of sleighs. But it is also interesting for coasting purposes because the skees will not sink in loose snow nearly as much as will the ordinary coasting sleds. It is also adapted for exercise and pleasure on ice covered bodies of water especially if 85 there is some snow on the ice.

What I claim is:

1. The combination with a pair of spaced skees of a transversely arranged frame having legs pivotally connected to the skees, and 90 a seat upon said frame, two rocker arms fixed one upon each skee, a horizontal bar pivoted with its ends to the rocker arms and having means for one of the lower limbs of a person occupying the seat to engage 95 and tilt or roll in unison the skees to either side and thereby steer them, and means for propelling the device forward.

2. The structure specified in claim 1, said seat being pivoted to swivel in horizontal 100 plane upon the frame, and having bracing rods extended from it and pivoted to the front points of the skees.

3. The structure specified in claim 2, said bracing rods having at the seat slid able 105 joints permitting automatic shortening of the rods when the skees are being tilted.

In testimony whereof I affix my signature.

SWAN HOLMGREN.
